UNITED STATES PATENT OFFICE.

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK.

WINDSHIELD.

Application filed August 23, 1926. Serial No. 131,008.

This invention relates generally to windshields and more particularly to windshield operating mechanism.

One of the objects of this invention is to provide an operating mechanism for windshields involving a unitary self-locking control and further mechanism of this character which is distinguished by its simplicity thereby enabling the same to be manufactured at a minimum cost and assembled with facility.

Another object of this invention is to provide a mechanism of this character which is inherently resilient so that shocks or jars occasioned to the windshield or to the frame are dissipated or minimized.

The several objects, and advantages of this invention as well as the details of construction wherein these advantages are attained will be made more apparent as this description proceeds especially when considered in connection with the accompanying drawings wherein

Figure 1 is a fragmentary vertical sectional view through a windshield construction constructed in accordance with this invention.

Figure 2 is a vertical transverse sectional view indicated by line 2—2 in Figure 1, and

Figure 3 is a longitudinal vertical section taken substantially on the plane indicated by line 3—3 in Figure 2.

Referring now particularly to the drawings wherein like reference characters indicate like parts, it will be noted that there is herein illustrated a windshield providing upper and lower sections 10 and 11, the lower section being swingingly mounted adjacent its upper edge on horizontally disposed pivots 12 carried by upright frame members 13. The lower sash 14 of the windshield 11 is formed with a longitudinally extending recess or pocket 15 in the lower edge thereof which cooperates with a weather strip 16 arranged in a rabbet formed in the upper face of the frame base 17.

The operating mechanism for swinging the windshield about its pivots 12 includes a housing indicated generally by the reference character 18 this housing being secured to the frame base 17 by means of laterally extending flanges 19 and securing screws 20. The tubular portion 21 of the housing is open at both ends and extending longitudi-

nally therethrough is a shaft or rod 22 to one end of which a handle 23 is secured. This handle is formed with a centrally arranged boss 24 which fits within the end of the tubular portion 21 of the housing and has a bearing engagement therewith. The other end of the shaft 22 is secured to a bearing plug 25 by means of a pin 26; this plug being formed with a boss or extension 27 projecting into the housing and having a bearing engagement therewith.

Associated with the shaft 22 for rotation therewith is a spiral member 28 preferably formed of resilient material, it being found that a coil spring may be employed in this connection with entire satisfaction. The spiral member 28 surrounds the shaft 22 and has one end anchored in a recess formed in the hub of the handle as indicated at 29 and the other end anchored in a recess formed in the boss 27 of the plug 25 as indicated at 30. The diameter of the convolutions of this spiral member is such that a clearance is provided between these convolutions and the shaft 22.

The reference character 31 indicates generally a runner or carrier which is movable longitudinally of the housing 18. This runner is provided with a cylindrical or tubular portion 32 which surrounds shaft 22, this runner extending upwardly from the shaft through a slot 33 formed in the tubular portion 21 of the housing. The runner is formed with a pair of spaced portions or ears 34 which receive therebetween one end of a link 35 this link being pivoted to these ears by means of a pivot pin 36. The other end of this link is pivoted as at 37 to a bracket 38 secured as at 39 to the sash 14 of the windshield.

The tubular portion 32 of the runner 31 is extended in the longitudinal direction of the shaft 22 so as to form a relatively long portion for engagement with this shaft whereupon a fore and aft rocking movement of the carrier or runner is prevented and this element properly guided in its movement longitudinally of the housing. Any lateral rocking movement of the runner is prevented by means of ribs 40 projecting laterally therefrom which engage the edges of the slot 33.

The runner or carrier is provided with an aperture 41 extending laterally therethrough and through which the spiral element 28 is

threaded. As a consequence of this construction when the handle 23 is rotated the shaft 22 and spiral element 28 will be likewise rotated and because of the engagement 5 between this latter element and the runner 31 this runner will be moved longitudinally of the housing through the slot 33 and along the shaft 22. The connection between the runner and windshield afforded by the 10 link 35 and bracket 38 causes an adjusting movement to be imparted to the windshield for swinging the same about its pivots 12.

Without further description it will be apparent that a unitary control is provided 15 and one which is self-locking so as to remain in its adjusted positions. By forming the element 23 of resilient material as for instance by using a coil spring, shocks or jars 20 imparted directly to the windshield or to the frame will be absorbed or dissipated so that these shocks, which in some instances prove disastrous to the windshield, are sufficiently minimized to be of no consequence. The structural characteristics of the device 25 permit the same to be manufactured economically and quickly and easily assembled.

While the device is illustrated herein as applied to the lower section of a double section windshield it will be readily apparent 30 that this operating mechanism will function with equal facility in connection with a single panel windshield and may also be employed in connection with windshields swinging both inwardly and outwardly with 35 reference to the frame. As a consequence reservation is made to make such changes and modifications in the invention as may come within the purview of the accompanying 40 claims.

40 1. What I claim as my invention is:

1. In combination, a swinging windshield, 45 a rectilinearly movable carrier, means for connecting said carrier to said windshield for adjusting the latter and means for actuating said carrier including a spiral resilient element connected therewith.

2. In combination, a swinging windshield, 50 a rectilinearly movable carrier, means for connecting said carrier to said windshield for adjusting the latter, means for actuating said carrier including a spiral resilient element, means for rotatively mounting said element and means for rotating said element.

55 3. In a windshield construction, a swinging windshield, a housing, a shaft therein, a runner guidingly supported by said housing and shaft for movement longitudinally thereof, a rotatable spiral member for moving 60 said runner and means connecting said

runner to said windshield for adjusting the latter.

4. In a windshield construction, a swinging windshield, a housing, a shaft therein, a runner guidingly supported by said housing and shaft for movement longitudinally thereof, a rotatable resilient spiral member for moving said runner and means connecting said runner to said windshield for adjusting the latter.

5. In a windshield construction, a swinging windshield, a housing, a shaft therein, a runner guidingly supported by said housing and shaft for movement longitudinally thereof, a spiral spring associated with said shaft for rotation therewith and engaging said runner for moving the same and means connecting said runner to said windshield for adjusting the latter.

6. In a windshield construction, a swingingly mounted windshield, a rotatable coil spring, a carrier movable thereby and means connecting said carrier and windshield.

7. In a windshield construction, a swinging windshield, a housing having a longitudinally extending slot therein, a shaft positioned within said housing, a runner guidingly supported upon said shaft and having an upstanding portion extending through said slot permitting a longitudinal movement thereof, a rotatable spiral member for moving said runner and means connecting the upstanding portion of said runner to said windshield for adjusting the latter.

8. In combination, a swinging windshield, 95 shield, a rectilinearly movable carrier, a rotatable spiral element extending through a lateral opening in said carrier for moving the latter and means connecting said carrier to said windshield for adjusting the latter.

9. In a windshield construction, a swinging windshield, a housing, a shaft therein, a runner guidingly supported by said housing and shaft for movement longitudinally thereof, a rotatable spiral element surrounding said shaft in spaced relation thereto for moving said runner, and means connecting said runner to said windshield for adjusting the latter.

10. In a windshield construction, a swingingly mounted windshield, a shaft, a rotatable spiral element surrounding said shaft in spaced relation thereto, a runner having a portion interposed between said shaft and spiral element and rectilinearly movable by the latter along the shaft and means connecting said windshield and runner for adjusting the former.

In testimony whereof I affix my signature.

WILLIAM S. PRITCHARD.
